United States Patent Office.

THEODORE G. MEIER, OF ST. LOUIS, MISSOURI, ASSIGNOR TO ST. LOUIS COTTON FACTORY.

Design No. 2,867, dated January 28, 1868.

DESIGN FOR A TRADE-MARK.

The Schedule referred to in these Letters Patent and making part of the same.

TO ALL WHOM IT MAY CONCERN:

Be it known that I, THEODORE G. MEIER, of the city of St. Louis, county of St. Louis, State of Missouri, have originated and produced a new Design for a Trade-Mark, of which the following is a full, clear, and exact description, reference being had to the annexed drawing, making a part of this specification.

My design consists of the front elevation of a three-story building, having a central tower, surmounted by the American flag, while in the rear, and rising above its roof, are seen a smoke-stack and steam-pipe, discharging their respective contents. On the face of the building, above the second-story windows, is seen the name "St. Louis Cotton Factory," twice repeated. Above the building are seen the words, "St. Louis Cotton Factory," united with fanciful scroll-work, which entirely encloses the central figure, as shown by the drawing.

This is intended to be used in the form of an engraving; but, if used as a brand, the impression will have such breaks in its various parts as may be necessary to give the requisite strength to the stencil or other plate on which the impression is made.

What I claim as my invention, and desire to secure by Letters Patent, is—

The design for a trade-mark, substantially as shown and described.

THEODORE G. MEIER.
